UNITED STATES PATENT OFFICE.

PHILIP MUELLER AND ANTON C. SCHUERMANN, OF DECATUR, ILLINOIS, ASSIGNORS
TO ADOLPH MUELLER, TRUSTEE, OF DECATUR, ILLINOIS.

HOUSING FOR WATER FIXTURES.

Application filed April 21, 1923. Serial No. 633,741.

To all whom it may concern:

Be it known that we, PHILIP MUELLER and ANTON C. SCHUERMANN, citizens of the United States, residing at Decatur, in the county of Macon and State of Illinois, have invented new and useful Improvements in Housings for Water Fixtures, of which the following is a specification.

The present development relates to fittings for water and similar fixtures, and has for its object to provide a fitting which will properly support and adequately house fittings so as to protect and conceal them, give a pleasing and ornamental appearance, and render the installation absolutely sanitary.

While the development is designed for various fittings, it will here be shown in connection with a supply regulator and waste fitting adapted for use with water supplies, as, for example, with drinking fountains, in connection with which last named fixtures it is highly essential that great attention be given to sanitation, as they are installed in public places and used indiscriminately by all classes of people.

It is desirable, in installing fixtures of this kind, that such installation should fully cover and protect them, but at the same time be of such character that it can be readily and quickly removed for the purposes of inspection, repair or replacement of the housed parts, and the present development is so constructed that the parts, while fully protected from handling or tampering by unauthorized persons, may be very readily reached for any needed attention.

In order that the invention may be clear to those skilled in the art, we have shown, in the accompanying drawings, embodiments of our invention, but it will be understood that the disclosure is illustrative and in no sense restrictive.

In said drawings:

Fig. 1 is a view in front elevation of our invention.

Fig. 2 is a longitudinal sectional view substantially through the vertical center of the installation shown in Fig. 1.

Fig. 3 is a view in front elevation of a slightly different form of the invention.

Fig. 4 is a view in section substantially on the vertical center of Fig. 3.

Referring to the drawings by numbers,

like numbers indicating like parts in the several views, 10 indicates any suitable support, as a wall or back slab.

To the support 10 is secured the base member 11 in any suitable manner, as by the lag screws 12, the said base member 11 being preferably formed of vitreous ware, although obviously it could be made of other material. Vitreous ware, however, because of its pleasing finish and sanitary qualities, is preferable.

The said base member 11 is provided with apertures therethrough which register with corresponding apertures in the support 10, and in the form shown in Figs. 1 and 2, these registering apertures are traversed by a supply pipe 13 and a waste pipe 14.

The supply pipe 13, in the present instance, has cut into it just in front of the base member 11 a pressure regulator 15, conventionally shown, and which may be of any desired type, it being essential in many installations, and particularly in drinking fountain installations that the city supply be so regulated and controlled as to give always a constant pressure at the outlet and maintain the drinking stream always at a certain height or angle.

The regulator 15 after it is once set should, of course, be guarded against unauthorized tampering, although it should be so arranged that it is readily accessible for any adjustments, repairs or replacements that may, from time to time, be necessary. In order to properly conceal and protect the regulator 15, there is provided a housing member 16 which, as shown in the present instance, is of substantially cruciform shape, the horizontal limb being of greater lateral depth than the vertical limb so as to take care of the laterally spreading parts of the fixture 15 and to give ample room for the coupling nipples which are engaged by the sections of the supply pipe 13.

The housing 16 will preferably be formed of vitreous ware and will seat snugly and flatly against the base member 11, the parts, when arranged, as shown in Figs. 1 and 2, presenting smooth outer surfaces, practically devoid of any retaining crevices so as to give a sanitary arrangement of parts and an ornamental and pleasing appearance.

The said housing member 16 has an aper-

ture at its front through which passes the supply pipe 13 leading to the point of delivery, which pipe 13 sustains the housing against vertical displacement. In order to hold the housing snugly in position, there is provided the sleeve 17 mounted upon the pipe 13 and adapted to be clamped in adjusted position in any suitable manner, as by the grub screw 18. Preferably, this sleeve 17 will have a wedging end to engage the aperture in the housing 16, and in the present form, that wedging end is shown as coned so that it will engage and center the housing 16 when it is forced forwardly along the pipe 13 into the aperture. In this position it will be tightly clamped to the pipe by the grub screw 18, and the housing 16 firmly held in properly centered position against the base member 11.

In order to securely clamp the housing 16 in place and prevent any shifting of it under pressure, which would possibly result in splintering the vitreous ware or other material at the orifice engaged by the wedging sleeve 17, there is provided the cup-shaped member 19 slidably engaged with the pipe 13 and provided with means for securing it to the sleeve 17. Preferably this will be secured by exteriorly threading the sleeve 17 and interiorly threading the cup-shaped member 19, so that the member 19 may be run up on the sleeve against the housing 16, thus giving an extended clamping area to more firmly hold the housing in place. To increase the clamping area we preferably flare the mouth of the cup-shaped member 19 as shown in Fig. 2 which results in a clamping action against the housing 16 over a considerable area. The cup-shaped member 19 may be properly finished so as to give an ornamental and pleasing appearance and add to the effectiveness of the installation.

With this construction it will be seen that while the fixture 15 will be completely concealed and protected, it may nevertheless be readily gotten at by simply running back the cup-shaped member 19, loosening the grub screw which holds the sleeve 17 to the pipe, slide the sleeve back on the pipe 13, and then slip the housing 16 away from the base member 11 so as to give access to the fixture for any attention which it may need. The waste 14, in the form shown in Fig. 2, is a concealed waste passing through the base member 11 and the support 10, and in order to finish the waste 14 at its coupling joint, there may be provided the escutcheon sleeve 20 having the extended friction bearing 21 at its forward end to engage closely the pipe 14 and maintain the escutcheon sleeve in the proper position snugly against the base member 11.

In that form of the invention shown in Figs. 3 and 4, the installation is adapted to a vertically disposed supply pipe, as dis-

tinguished from the concealed supply pipe which passes through the wall or support in Figs. 1 and 2.

The parts are generally the same as in the form heretofore described, there being provided the support 22 to which is secured the base member 23, this base member being fastened to the support in any suitable manner, as by lag screws 24.

The said base member 23 is, however, recessed as shown and provided with a supply pipe aperture 25 in its front wall and a supply pipe aperture 26 in an end wall, as shown in Fig. 4. The recess in the back of the base member 23 provides for the vertical supply pipe which passes up along the support through the end wall aperture 26 and engages an elbow coupling 27 secured in any suitable manner, as by the screws 28, to the support 23. The elbow coupling 27 connects with the horizontal limb 29 of the supply pipe which passes through the aperture 25 in the front wall of the base member 23. The supply pipe 29 has cut into it the regulator 30, and this regulator 30 is concealed within the housing 31 exactly as shown and described in Figs. 1 and 2. The clamping sleeve 32 secured to the supply pipe 29 and the cup-shaped clamping member 33 are identical with the sleeve and clamping member heretofore described, and function in the same manner.

Where exposed plumbing is used, waste from the drinking fountain or other point of delivery will, of course, pass directly through the floor, or be led to any suitable point.

From the foregoing it will be seen that an installation is provided which will take care of either concealed or exposed plumbing, which will conceal and adequately protect fittings of the character such as is exemplified by the pressure regulator used as an illustration, and yet one in which ready access to the fixtures may be had.

Such changes and substitutions as amount merely to mechanical skill may, of course, be made without departing from the invention.

We claim:

1. In a fitting of the class described, the combination of a base member having pipe-receiving apertures therein, means for securing said base member to a suitable support, a fixture-housing member having a pipe-receiving aperture therein and adapted to be seated upon said base member, and concealed means to hold said housing member in place upon said base member.
2. In a fitting of the class described, the combination of a recessed base member having pipe-receiving apertures therein, means for securing said base member to a suitable support, a fixture-housing member having a pipe-receiving aperture therein and adapted to be seated upon said base member, and

concealed means to hold said housing member in place upon said base member.

3. In a fitting of the class described, the combination of a base member having pipe-receiving apertures therein disposed at substantially right angles to one another, means for securing said base member to a suitable support, a fixture-housing member having a pipe-receiving aperture therein and adapted to be seated upon said base member, and means to hold said housing member in place upon said base member.

4. In a fitting of the class described, the combination of a base member having a pipe-receiving aperture in its front wall and a pipe-receiving aperture in its end wall, means for securing said base member to a suitable support, a fixture-housing member having a pipe-receiving aperture therein and adapted to be seated upon said base member, and means to hold said housing member in place upon said base member.

5. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing its aperture, and concealed means to hold said housing member in place upon said base member.

6. In a fitting of the class described, the combination of a base member having pipe-receiving apertures therein, means for securing said base member to a suitable support, a fixture housing member having a pipe-receiving aperture adapted to be seated upon said base member and sustained against vertical displacement by a pipe traversing its aperture, and concealed means to hold said housing member in place upon said base member carried by said pipe.

45 7. In a fitting of the class described, the combination of a base member having pipe-receiving apertures therein, means for securing said base member to a suitable support, a fixture-housing member having a pipe-receiving aperture adapted to be seated upon said base member and sustained against displacement by a pipe traversing its aperture, a sleeve secured to said pipe and engaging said housing to hold it in position upon said base member, and a pipe-receiving clamping member enclosing said sleeve and bearing against the housing.

8. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing

its aperture, and a wedging sleeve secured to said pipe and engaging the aperture in said housing to hold it in position upon said base member.

9. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing its aperture, a sleeve secured to said pipe, and a clamping member adjustably mounted on said sleeve to engage said housing and hold it in position upon said base member.

10. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing its aperture, a sleeve secured to said pipe, and a pipe-receiving clamping member adjustably mounted on said sleeve to engage said housing and hold it in position upon said base member.

11. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing its aperture, a sleeve secured to said pipe, and a pipe-receiving clamping member adjustably mounted on and enclosing said sleeve to engage said housing and hold it in position upon said base member.

12. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe traversing its aperture, an exteriorly threaded sleeve secured to said pipe, and a pipe-receiving clamping member enclosing and in threaded engagement with said sleeve to engage said housing and hold it in position upon said base member.

13. In a fitting of the class described, the combination of a base member having pipe-receiving apertures therein, means for securing said base member to a suitable support, a fixture-housing member having a pipe-receiving aperture adapted to be seated upon said base member and sustained against vertical displacement by a pipe

traversing its aperture, an exteriorly threaded sleeve secured to said pipe, and a pipe-receiving clamping member having a flaring mouth enclosing and in threaded engagement with said sleeve to engage said housing and hold it in position upon said base member.

14. A hollow housing of the class described of substantially cruciform shape.

15. A hollow housing of the class described of substantially cruciform shape and having one member of greater depth laterally than its other member.

16. A hollow housing of the class described of substantially cruciform shape and having its horizontal member of greater depth laterally than its vertical member.

17. In a fitting of the class described, the combination of a base member having exposed front and side faces and provided with a pipe receiving aperture in its front face, means for securing said base member to a suitable support, a fixture housing member adapted to be seated upon said base member about the pipe aperture in the front face thereof and having an aperture adapted to receive a pipe that will sustain the housing against vertical displacement, a sleeve adapted to be secured to the pipe projecting from the housing and to hold the housing in close contact with the base member, and a member adapted to be fitted to said projecting portion of the pipe and to enclose and conceal said sleeve.

18. In a fitting of the class described, the combination of a base member having exposed front and side faces and provided with a pipe receiving aperture in its front face, means for securing said base member to a suitable support, a fixture housing member adapted to be seated upon said base member about the pipe aperture in the front face thereof fitted to the pipe projecting from the housing, a screw for securing said sleeve to the pipe to hold the housing against

the base member, and a cup-shaped member adapted to be fitted to the pipe and to enclose said sleeve and conceal the same and the fastening screw.

19. In a fitting of the class described, the combination of a base member having exposed front and side faces and provided with a pipe receiving aperture in its front face, means for securing said base member to a suitable support, a fixture housing member adapted to be seated upon said base member about the pipe aperture in the front face thereof and having an aperture adapted to receive a pipe that will sustain the housing against vertical displacement, a sleeve adapted to be fitted to the pipe projecting from the housing, a screw for securing said sleeve to the pipe to hold the housing against the base member, and a cup-shaped member adapted to be fitted to the pipe and engage with said sleeve, said member assisting to hold the fixture housing against the base and to conceal said sleeve and screw.

20. In a fitting of the class described, the combination of a base member having exposed front and side faces and provided in its front and lower side faces with pipe receiving apertures, means for securing said base member to a suitable support, a fixture housing member adapted to be seated upon the base member about the pipe aperture in the front face thereof and having an aperture adapted to receive a pipe that will sustain the housing against vertical displacement, means adapted to be secured on the pipe projecting from the opening in said housing and to hold the housing in close contact with the base member, and means adapted to be fitted to said pipe and conceal said fastening means.

In testimony whereof we have hereunto set our hands.

PHILIP MUELLER.
ANTON C. SCHUERMANN.
